MECHANICAL RELAY APPARATUS

John F. Schock, Philadelphia, Pa., assignor to
Leeds and Northrup Company, Philadelphia,
Pa., a corporation of Pennsylvania

Application January 31, 1935, Serial No. 4,214

18 Claims. (Cl. 74—1)

My invention relates to mechanical relay apparatus; that is, apparatus for reproducing the motion of a primary movable member with an amplified torque and/or displacement. While my invention is of general application, it is particularly suitable for use as a component of an electrical measuring and recording apparatus of the type shown in United States Letters Patent #1,935,732, granted November 21, 1933, to 10 L. Y. Squibb, upon which the present application constitutes an improvement.

In accordance with my invention, a mechanical relay apparatus, such as illustrated and described in the Squibb patent, constitutes essentially a primary movable member, a pair of feelers disposed to engage opposite sides of the member, means for intermittently separating the feelers, means operable during the inoperative periods of the separating means to move 20 the feelers towards engagement with the primary movable member in any position within its range of movement, and a secondary member that is movable by or in accordance with the movement of the feelers into engagement with the primary movable member. Such apparatus generally includes also a movable member effective to integrate movements of the secondary movable member and operable thereby through periodically engageable clutch mechanism and a suitable source of power.

In accordance with my invention, the response and accuracy of relay apparatus of the type just described, is for small deflections of the primary movable member, controlled by provision for 35 adjusting the clearance between the feelers and the primary movable member when in engaging relationship. Such an adjustment imparts to the apparatus the highest degree of response and accuracy in cases where this is desired, while, 40 on the other hand, permits a lower sensitivity to be obtained when the apparatus is utilized in the measurement of a rapidly varying quantity and it is desired to eliminate such rapid variations of low amplitude, or in control systems in which 45 too high a sensitivity may tend toward oscillation of the system.

On the other hand, the introduction of an appreciable clearance between the feelers and the primary movable member may give rise to 50 "creeping", that is, cumulative errors imparted to the integrating mechanism, in case the timing of the feelers is not accurately adjusted. Therefore, further in accordance with my invention, I provide means for independently adjusting the 55 timing of the release of the feelers by the means

which operates to separate them intermittently.

For a better understanding of my invention, together with other and further features thereof, reference is had to the following description taken in connection with the accompanying drawing, and its scope will be pointed out in the appended claims.

In the drawing, Fig. 1, is a view, in front elevation, of my improved mechanical relay apparatus, per se;

Fig. 2 is a cross-sectional view of the relay apparatus along the lines 2—2 of Fig. 1 and including, also, a portion of an associated measuring instrument of the type described in the above-mentioned Squibb patent.

Fig. 2a is a detail of a bearing stud of Fig. 2;

Fig. 3 is a detail of the mechanism for adjusting the clearance between the feelers and the primary movable element;

Fig. 4 is a detail view of the cam structure of 20 Figs. 1 and 2 effective intermittently to separate the feelers; while Figs. 5 and 6 are cross-sectional views of the cam along the lines 5—5 and 6—6, respectively, of Fig. 4.

Referring now more particularly to Figs. 1 and 2 of the drawing, there is shown a mechanical relay apparatus comprising a supporting base or plate 10 upon which are pivotally mounted a pair of feelers or scissors-like arms 11 and 11a having extending arms or brackets 12, 12a secured to pivot pins 13, 13a (only the bracket 12 and associated pivot 13 being shown in the drawing), which are supported between a bracket 14 secured to the plate 10 and adjustable studs 15 and 15a. The studs 15, 15a are provided with 35 cylindrical recesses 15b in which are disposed hardened steel balls 15c forming bearings for the pivot pins 13, 13a (Fig. 2a). The plate 10, omitted in Fig. 1 for the sake of clarity, is provided with a projection 10a folded back substantially parallel to the plate through which projects a screw 16 threaded into the plate 10 and serving as a locking device for the studs 15, 15a which are threaded through the plate 10 and projection 10a. A spring plate 17 is secured to the depending arm of the bracket 14 to retain the pivot pins 13, 13a in position and to provide a thrust for seating them accurately in the bearing recesses of the studs 15, 15a. The feelers 11, 11a are provided with extending arms 18, 18a, respectively, interconnected by a biasing spring 19, effective to urge the feelers 11, 11a into engagement, that is, to close the grips of the scissors. Attached to the extending brackets 12, 12a

of the feelers 11, 11a are cam followers 20, 20a, respectively.

The plate 10, upon which is secured the above-described feelers, is mounted adjacent a continuously rotating shaft 21 upon which is secured a cam structure 22 (Figs. 4, 5 and 6) having cam elements 23 and 23a cooperating with the cam followers 20, 20a intermittently to separate the feelers 11, 11a for a predetermined portion of each revolution of the shaft 21. The feelers 11, 11a are disposed to engage opposite sides of a primary movable member, such as a deflecting pointer 24 secured to the movable coil 25 of a galvanometer assembly 26, only a fragmentary portion of which is shown for the sake of clarity, since the galvanometer may be of any of the several types well-known in the art and, per se, constitutes no part of my present invention.

The feelers 11, 11a also engage opposite sides of a pin assembly 27 interposed between the lower arms thereof and secured in a slot 28 of an upstanding bracket 29 of a secondary movable member or clutch member 30 which, together with an upstanding arm or bracket 30a thereof, is secured to a pivot pin 31 supported in a bearing in the plate 10 and a second bearing in a bracket 32, a spring plate 32a secured to the bracket 32 being effective to retain the pivot pin 31 properly positioned within its bearings. A face plate 33, 30 secured to the front of the base 10 as by screws 33a, forms a bearing for the pivot pin 31 to take the thrust of the spring plate 32a. The base plate 10 has a pair of extending arms 10b pivoted at 10c in a supporting frame 34 of the apparatus, 35 on which is mounted also the galvanometer assembly 26. The base plate 10 and the above-described apparatus supported therefrom is biased into engagement with the frame 34 as by a spring 35 interconnecting the frame and the lower tip of the plate 10. Secured to the base plate 10 are a pair of studs 36 provided with cam surfaces 36a and secured in position by lock nuts 36b. The cam surfaces 36a respectively cooperate with a pair of cam elements 37, comprising an integral 45 part of the cam structure 22, which are effective intermittently to move the base plate 10 and its associated apparatus about its pivot 10c through a small angle against the bias of the spring 35.

A detail of the structure of the pin assembly 27 is shown in Fig. 3. This assembly comprises a threaded stud 38 and a cooperating nut 39 having guideways 39a which engage the edges of the slot 28 in which the pin assembly is supported to prevent rotation of right hand conical member 40. 55 Loosely mounted on the stud 38 are a pair of frusto-conical members 40 between which is supported an expansible split sleeve or collar 41. A locking key 42 is supported on the stud 38 and engages a flat 39b of the nut 39 and extends into 60 the slit in the collar 41. The conical members 40 are urged into engagement by means of a nut 43 and a lock nut 45 for maintaining the desired pin adjustment.

Projecting from the clutch member 30 are a 65 pair of extending arms 30a on which are supported cam followers 30b cooperating with cams 46 (only one of which is shown), attached to the shaft 21. Directly behind the base plate 10 and substantially coaxial with the pin 31, upon which 70 the clutch member 30 is supported, is a clutch disk 47 journalled in the frame 34. The clutch disk 47 is actuated by the clutch member 30 through a pair of clutch disks or shoes 48 of cork or other suitable clutching material. At the 75 other end of the shaft 47a, upon which the clutch

disk 47 is mounted, may be located a suitable pulley or shaft 49 and slidewire or control disk 50, in case the apparatus is to be utilized in a recorder of the type disclosed in the Squibb patent, the pulley 49 controlling the recording pen and the disk 50, the measuring circuit of the galvanometer 26 and/or any controlled circuit.

Referring to Fig. 2, there is also pivotally supported at 10c a U-shaped bracket 51 having a depending arm 51a terminating in a horizontally 10 extending portion cooperating with a cam element 52 of the cam 22 (Figs. 4 and 6). Secured to the bracket 51 is a resilient arm or clamping element 53 adapted to engage the pointer 24 of the galvanometer 26 with a complementary 15 clamping element 54 secured to the apparatus frame 34.

The general principles of operation of the above-described apparatus are substantially identical with those of the apparatus described in the 20 aforesaid Squibb patent upon which my invention constitutes an improvement. Briefly, assuming the several elements to occupy the relative positions indicated in Figs. 1 and 2 of the drawing and the rotation of the shaft 21 to be counter-clockwise, as indicated by the arrow in Fig. 2, it will be seen that the cam elements 37 are disengaging the cam surfaces of the studs 36 secured to the base plate 10, so that it is retracted by its biasing spring 35 to the position in which the clutch elements 48 of the clutch member 30 engage clutch disk 47. At substantially the same time, the cam elements 23 and 23a are just engaging the cam followers 20 and 20a, respectively, and upon rotation of the shaft 21, these cam elements are effective to move, against the bias of the spring 35, the feelers 11, 11a about their pivots 13, 13a, in opposite directions away from the galvanometer needle 24. The cams 46 thereafter engage with either of the cam followers 30b of the clutch member 30 which has been deflected into its path of rotation and, upon rotation by the shaft 21, effect movement of the clutch element 30 about its pivot 31 to a horizontal position and coincident rotation of the clutch disk 47.

During the aforesaid portion of the cycle of rotation of the shaft 21 in which the clutch disk 47 is being moved through an angle proportional to the deflection of the clutch member 30 which, in turn, is proportional to the deflection of the galvanometer needle 24, as described hereinafter, the cam element 52 disengages the arm 51b of the bracket 51, releasing the galvanometer needle 24 from between the clamping elements 53 and 54. The needle 24, under the influence of its actuating coil 25, now deflects to a position corresponding to, and constituting a measure of, any particular electrical condition being measured. As may be seen from the configuration of the cam elements 23, 23a and 52, (Figs. 5 and 6), the galvanometer needle 24 is disengaged by the feelers 11 and 11a and remains unclamped by the elements 53 and 54 during a larger portion of the cycle of rotation of the shaft 21, thereby allowing a maximum time for the galvanometer needle 24 to come to rest with a deflection corresponding to the new value of the condition being measured.

Thereafter, the cam elements 37 engage the cam studs 36 to move the base plate 10 through a small angle about its pivot 10c, separating the clutch disk 47 and the clutch member 30 so that the member 30 is entirely free. At about the same time the cam 52 engages the depending arm 51a of the bracket 51, which operates to clamp the galvanometer needle 24 between the elements 75

53 and 54 in its new deflected position. Substantially simultaneously with, or shortly after, the clamping of the needle 24, the cam elements 23 and 23a disengage the cam followers 20 and 20a 5 and release the feelers 11, 11a, respectively. Prior to the release it is to be observed the cam elements 23 and 23a maintain the feelers 11 and 11a spaced apart by equal amounts from their neutral position illustrated in Fig. 1. Upon release, however, 10 the biasing spring 19 is effective to move the feelers toward each other, closing the scissors and engaging the galvanometer needle 24 and the pin assembly 27 in their complementary grips. The spring 19 will return the feelers 11 and 11a toward 15 their neutral position at substantially the same speeds so that if the needle 24 has been deflected through a substantial angle, one of the feelers will engage the needle before the other. Spring 19 will thereupon move the other feeler about 20 its pivot to the inclined position corresponding to the deflection of the needle 24, the lower arm of that feeler, when moving past the neutral position, engaging the pin assembly 27 and deflecting it, together with the clutch member 30, about its pivot pin 31. Thereupon, the 25 cam elements 23 and 23a again separate the feelers 11, 11a, the cam 52 disengages the arm or element 51a to unclamp the galvanometer needle from between the elements 53 and 54, as described 30 above, and the above described cycle of operation is repeated.

From the foregoing, it is clear that the deflection of the galvanometer needle 24 is measured once each revolution of the shaft 21, and this deflection is imparted through a torque and/or displacement amplifying mechanism once each cycle to the secondary movable member or clutch member 30. If it were desired merely to reproduce intermittently such amplified movements of the pointer 24, the apparatus might stop there, and the clutch disk and associated apparatus be omitted. However, it is often desirable to integrate the deflections of the galvanometer needle 24, and this is done by the above-described apparatus, it being clear that once each cycle of rotation of the shaft 21, the disk 41 is moved through an angle corresponding to the instant deflection of the galvanometer in both magnitude and sense, which movements are added algebraically, 50 or integrated.

The response of the above apparatus may be adjusted by releasing the stud 38 in nut 39 and sliding the pin assembly 27 up or down in the slot 28 of the clutch member 30, thus varying the 55 radius of the operating arm of the clutch member relative to the radius of the lower arms of the feelers 11 and 11a about their respective pivots. In addition to thus affording an adjustable connection for operating the clutch member 30, the collar 41 of the pin assembly 27 serves also to limit the closing of the scissors-like feelers 11, 11a by the biasing spring 19 which, in turn, determines the clearance between feelers 11 and 11a and the pointer 24 when in engaging relationship. 60 This clearance may be adjusted by adjusting the nut 43, which determines the spacing between the conical members 40 and thus the expansion of the spring collar or sleeve 41. This may be accomplished from the front of the apparatus since the nut 39, which restrains the movement of the right-hand conical member (Fig. 3) is prevented from rotation by engaging the slot 28, as described 65 above.

This adjustment of the clearance between the 70 feelers 11, 11a and the pointer 24 is very desirable

for maximum flexibility of the apparatus. For example, when it is desired to secure maximum sensitivity of the apparatus, that is, response of the relay apparatus to minimum deflections of the pointer 24, a minimum clearance should be provided between the feelers 11, 11a and the pointer 24 so that even infinitesimal deflections of the pointer 24 will be registered by one or the other of the feelers 11, 11a. On the other hand, if an appreciable clearance be introduced between the 10 feelers 11, 11a, and the pointer 24, it is clear that deflections of the pointer 24 within the range of clearance will be ineffective to produce a movement of the secondary member 30 or the clutch disk 41. However, in certain instances, this is 15 desirable as, for example, when the quantity to which the galvanometer 26 is responsive has a rapidly fluctuating component or ripple which it is desired to eliminate from the reproduced movement of the secondary member 30; or, in 20 instances where the apparatus is utilized in controlling the condition to which the galvanometer 26 is responsive and in which too high a sensitivity of the apparatus produces oscillations or hunting in the control system as a whole. 25

On the other hand, when the sensitivity of the apparatus is limited by introducing an appreciable clearance between the feelers 11 and 11a and the pointer 24, it sometimes occurs that the apparatus develops a tendency to "creep"; that is, to produce a cumulative movement of the disk 41 in a given direction irrespective of variations in the condition to which the galvanometer 26 is responsive. It has been found that this error is occasioned by slight differences in 30 the timing of the release of the feelers 11, 11a by the cam elements 23, 23a, respectively. For example, if the cam 23 releases its cooperating feeler 11 by a very slight interval ahead of the release of the feeler 11a, the biasing spring 19 will 35 tend to return the feeler 11 into engagement with the pointer 24 before engagement thereof by the feeler 11a. The result is that, for deflections of the pointer 24 within the range of the clearance between the pointer and the feelers 11 and 11a, the feeler 11 will always deflect the pointer in the same direction by the amount of the clearance, and these unidirectional deflections are cumulative. 40

The above error can be eliminated, in accordance with my invention, by adjusting the feelers 11, 11a along their pivotal axes by means of the adjusting screws 15, 15a, respectively, one end of each of which constitutes the pivotal bearing for its respective feeler pivot pin. As seen more clearly in Fig. 2, such an adjustment of the feelers along their pivotal axes moves their associated cam followers 20, 20a substantially tangentially to the path of their respective cam elements 23, 23a. For example, if the screw 15a be turned to the right, moving the pivot pin 13a against the bias of the plate-spring 17, the cam follower 20a will descend the trailing edge of the cam element 23a, thus releasing the feeler 11a, at a somewhat earlier point in the cycle of rotation in the shaft 21. Thus, if there is found to be any tendency of the apparatus to "creep", as described above, this may be completely removed by adjusting one or the other of the screws 15, 15a to adjust the corresponding pivoted feeler along its pivotal axis. When so adjusted, the feelers may be locked in the adjusted position by means of the locking screw 16. 50

While I have illustrated my improved mechanical relay apparatus as embodied in a control ap- 55 60 65 70 75

paratus of the type described in the above-mentioned Squibb patent, for adjusting the setting of a potentiometer disk 50 and a recording pulley 49 in accordance with the deflections of a galvanometer 26, it will be readily apparent to those skilled in the art that it is equally applicable to all systems in which it is desired to reproduce the movement of a primary movable member with an amplified torque and/or displacement.

While I have described what I at present consider the preferred embodiment of my invention, it will be obvious to those skilled in the art that various changes and modifications may be made without departing from my invention, and I, therefore, aim in the appended claims to cover all such changes and modifications as fall within the true spirit and scope of my invention.

What I claim is:

- 20 1. The combination with a mechanical relay apparatus comprising a primary movable member, a pair of feelers disposed to engage opposite sides of said member, means for intermittently separating said feelers, means operable during inoperative periods of said separating means to move said feelers substantially into engagement with said member in any position within its range of movement, a secondary member movable in accordance with the position of said feelers when engaging said primary member, of means for procuring an adjustable clearance between said feelers and said member when in engaging relationship to adjust the sensitivity of the apparatus.
- 30 2. The combination with a mechanical relay comprising a primary movable member, a pair of feelers disposed to engage opposite sides of said member, means for intermittently separating said feelers, means operable during inoperative periods of said separating means to move said feelers substantially into engagement with said member in any position within its range of movement, a secondary member movable in accordance with the position of said feelers when engaging said primary member, means independent of said primary member for limiting the movement of both of said feelers toward each other, of means for adjusting said limiting means to change said limits of movement of both feelers and simultaneously to adjust the clearance between said feelers and said primary member.
- 40 3. The combination with a mechanical relay comprising a primary movable member, a pair of feelers disposed to engage opposite sides of said member, means for intermittently separating said feelers, means operable during inoperative periods of said separating means to move said feelers substantially into engagement with said member in any position within its range of movement, a secondary member movable in accordance with the position of said feelers when engaging said primary member, of an expansible member interposed between said feelers to be engaged thereby when said feelers occupy a given angular position, and means for varying the expansion of said expansible member to change said angular position and simultaneously to adjust the clearance between said feelers and said primary member.
- 50 4. The combination with a mechanical relay comprising a primary movable member, a pair of feelers disposed to engage opposite sides of said member, means for intermittently separating said feelers, means operable during inoperative periods of said separating means to move

said feelers substantially into engagement with said member in any position within its range of movement, a secondary movable member, of an expansible member carried by said secondary member and interposed between said feelers to be engaged thereby, whereby said secondary member is moved by said feelers in accordance with the position of said feelers when engaging said primary member, and means for varying the expansion of said expansible member to adjust the clearance between said feelers and said member.

5. The combination with a mechanical relay comprising a primary movable member, a pair of scissors-like feelers disposed to engage said member in one of their grips, means for intermittently separating said feelers from a given angular position, a biasing spring interconnecting said feelers and operable during inoperative periods of said separating means to move said feelers substantially into engagement with said member in any position within its range of movement, a secondary movable member, of an expansible member carried by said secondary member and disposed to be engaged by the complementary grips of said feelers, whereby said secondary member is moved by said feelers in accordance with the position of said feelers when engaging said primary member, and means for varying the expansion of said expansible member to adjust the clearance between said feelers and said primary member by changing said given angular position of said feelers.

6. The combination with a mechanical relay comprising a primary movable member, a pair of feelers disposed to engage opposite sides of said member, means for intermittently separating said feelers, means operable during inoperative periods of said separating means to move said feelers substantially into engagement with said member in any position within its range of movement, a secondary member movable in accordance with the position of said feelers when engaging said primary member, of means operatively associated with both of said feelers for procuring an appreciable clearance between said feelers and said member when in engaging relationship to control the sensitivity of the apparatus, and means for independently adjusting the timing of the release of said feelers by said separating means.

7. The combination with a mechanical relay comprising a primary movable member, a pair of feelers disposed to engage opposite sides of said member, means disposed adjacent said feelers operable intermittently to separate the same, means operable during inoperative periods of said separating means to move said feelers substantially into engagement with said member in any position within its range of movement, a secondary member movable in accordance with the position of said feelers when engaging said primary member, of means operatively associated with both of said feelers for procuring an appreciable clearance between said feelers and said member when in engaging relationship to limit the sensitivity of the apparatus, and means for independently adjusting the spacing of said feelers with respect to said separating means to adjust the timing of the release of said feelers.

8. The combination with a mechanical relay comprising a primary movable member, a pair of pivotally mounted feelers disposed to engage opposite sides of said member, means disposed

- adjacent said feelers operable intermittently to separate the same, means operable during inoperative periods of said separating means to move said feelers substantially into engagement 5 with said member in any position within its range of movement, a secondary member movable in accordance with the position of said feelers when engaging said primary member, of means for procuring an appreciable clearance between said 10 feelers and said member when in engaging relationship to limit to a predetermined degree the sensitivity of the apparatus, and means for independently moving said feelers along their respective pivotal axes to adjust the timing of the 15 release of said feelers.
9. The combination with a mechanical relay apparatus comprising a primary movable member, a pair of feelers disposed to engage opposite sides of said member, a continuously rotating 20 cam disposed adjacent said feelers and operable intermittently to separate the same, means operable during inoperative periods of said separating means to move said feelers substantially into engagement with said member in any position 25 within its range of movement, a secondary member movable in accordance with the position of said feelers when engaging said primary member, of means for procuring an appreciable clearance between said feelers and said member 30 when in engaging relationship to limit the sensitivity of the apparatus, and means for independently adjusting the spacing of said feelers with respect to said cam to adjust the timing of the release of said feelers by said cam.
- 35 10. The combination with a mechanical relay apparatus comprising a primary movable member, a pair of pivotally mounted feelers disposed to engage opposite sides of said member, a continuously rotating cam disposed adjacent said 40 feelers and operable intermittently to separate the same, means operable during inoperative periods of said separating means to move said feelers substantially into engagement with said member in any position within its range of movement, a secondary member movable in accordance 45 with the position of said feelers when engaging said primary member, of means for procuring an appreciable clearance between said feelers and said member when in engaging relationship to limit the sensitivity of the apparatus, and means for independently moving said feelers along their respective pivotal axes to adjust the timing of the release of said cam.
- 50 11. The combination with a mechanical relay apparatus comprising a primary movable member, a pair of scissors-like feelers disposed to engage said member in one of their grips, each of said feelers including a unitary pivot pin with 55 which it is pivotally supported, a continuously rotating cam disposed adjacent said feelers and operable intermittently to separate the same, a biasing spring interconnecting said feelers and operable during inoperative periods of said separating means to move said feelers substantially into engagement with said member in any position within its range of movement, a secondary member movable in accordance with the position of said feelers when engaging said primary member, of means for procuring an appreciable clearance 60 between said feelers and said member when in engaging relationship to limit the sensitivity of the apparatus, means for biasing said pivot pins along their axes, and means for independently moving said feelers along their respective pivotal axes to adjust the timing of the release of said feelers by said cam.
- 65 12. The combination with a mechanical relay apparatus comprising a primary movable member, a pair of feelers disposed to engage opposite sides of said member, means for intermittently separating said feelers, means operable during inoperative periods of said separating means to move said feelers substantially into engagement with said member in any position within its range of movement, a driving clutch member movable in accordance with the position of said feelers when engaging said primary member, a driven clutch member, means for intermittently disengaging said clutch members during the release of said feelers and releasing them for reengagement upon the separation of said 70 feelers, means for intermittently returning said driving clutch member to a neutral position while engaged with said driven clutch member to integrate movements of said primary member, of means for procuring an appreciable clearance between said feelers and said member when in engaging relationship to adjust the sensitivity of the apparatus, and means for independently adjusting the timing of the release of said feelers by said separating means to eliminate creeping of said driven clutch member due to the clearance between said feelers and said primary member.
- 75 13. The combination with a mechanical relay apparatus, having a pair of feelers biased toward each other to move a secondary member in sense and magnitude corresponding to deflection of a deflecting member, an appreciable clearance normally being present between said feelers and said members to prevent positive movement of said secondary member upon small deflections of said deflecting member, of means for procuring positive and coextensive movement of said secondary member for small deflections of said deflecting member comprising an assembly carried by said secondary member for simultaneously varying the positions of said feelers until both feelers simultaneously engage said members.
14. A mechanical relay apparatus, having a pair of pivotal feelers biased into engagement with opposite sides of a deflecting member and separable therefrom by cam surfaces the feelers upon release by said cam surfaces selectively engaging a secondary member to move it in accordance with the extent and direction of the deflection of said deflecting member, characterized by an adjustable member disposed between said feelers and carried by said secondary member, means for adjusting said member simultaneously to rotate said feelers about their pivots substantially to eliminate clearance between said feelers and said primary member, and means for timing the release of said feelers by said cam surfaces for simultaneous movement toward said primary and secondary members comprising means for bodily moving each of said feelers along the axis of its pivot thereby to vary its relation with respect to its associated cam surface.
15. The combination with a mechanical relay having a pair of feelers pivoted intermediate their ends and biased toward a closed position to engage on one side of their pivots a deflecting member and upon substantial deflection thereof to engage a secondary member on the opposite sides of their pivots to move it an amount cor-

responding to said deflection an appreciable clearance normally being present between said feelers and said member to prevent positive movement of said secondary member upon small deflections of said deflecting member, of means for eliminating said clearance and for insuring positive and coextensive movement of said secondary member for small and large deflections of said deflecting member comprising an adjustable assembly carried by said secondary member and interposed between the ends of said feelers, and means for adjusting said assembly to move each of said feelers to positions simultaneously to engage said deflecting member and said assembly.

15. 16. The combination with a mechanical relay comprising a primary movable member having a given range of movement, a pair of pivotally mounted feelers disposed to engage opposite sides of said member, means disposed adjacent said feelers and operable intermittently to separate the same, means operable during inoperative periods of said separating means to move said feelers substantially into engagement with said member in any position within its range of movement, and a secondary member movable in accordance with the position of said feelers when engaging said primary member, of means for independently moving said feelers along their respective pivotal axes to adjust the timing of the release of said feelers.

20. 17. The combination with a mechanical relay apparatus comprising a primary movable member, a pair of scissors-like feelers disposed to en-

gage said member in one of their grips, each of said feelers including a unitary pivot pin by which it is pivotally supported, a continuously rotating cam disposed adjacent said feelers and operable intermittently to separate the same, a biasing spring connecting said feelers and operable during inoperative periods of said separating means to move said feelers substantially into engagement with said member, and a secondary member movable in accordance with the position of said feelers when engaging said primary member, of means for biasing each of said pivot pins along its axis, and means for independently moving each of said feelers along its pivotal axis against said biasing means to adjust the timing of the release of said feelers by said cam.

25. 18. A mechanical relay apparatus, having a pair of pivotal feelers biased into engagement with opposite sides of a deflecting member and separable therefrom by cam surfaces, the feelers upon release by said cam surfaces selectively engaging a secondary member to move it in accordance with the extent and direction of the deflection of said deflecting member, characterized by means for timing the release of said feelers by said cam surfaces for simultaneous movement toward said primary and secondary members comprising means for bodily moving each of said feelers along the axis of its pivot thereby to vary the relation of each feeler with respect to its associated cam surface.

JOHN F. SCHOCK.
